UNITED STATES PATENT OFFICE.

FRED B. KNOPP, OF UNION CITY, OKLAHOMA.

MAIL-BAG CATCHER AND DELIVERER.

1,154,323.

Specification of Letters Patent. Patented Sept. 21, 1915.

Application filed June 23, 1915. Serial No. 35,814.

To all whom it may concern:

Be it known that I, FRED B. KNOPP, a citizen of the United States, residing at Union City, in the county of Canadian and State of Oklahoma, have invented certain new and useful Improvements in Mail-Bag Catchers and Deliverers, of which the following is a specification.

The present invention relates to certain new and useful improvements in mail bag catchers and deliverers, and has for its object to provide a device of this character which embodies novel features of construction whereby mail sacks can be delivered to and from moving trains with certainty and without tearing or mutilating the sacks.

Further objects of the invention are to provide a device of this character which is comparatively simple and inexpensive in its construction, which is positive and reliable in its operation, which is not liable to get out of adjustment or repair, and which can be easily manipulated.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a mail bag catching and delivering device constructed in accordance with the invention, showing the same as applied to the side of a car and as swung upwardly into operative position. Fig. 2 is a similar view showing the device as collapsed against the side of the car. Fig. 3 is a vertical sectional view on the line 3—3 of Fig. 1, the device being shown by full lines in operative position and by dotted lines in inoperative position. Fig. 4 is a bottom plan view of the trap door which is provided at the bottom of the mail bag delivering cage.

Corresponding and like parts are referred to in the following description and indicated in all the views of the drawing by the same reference characters.

Referring to the drawings, the reference character A designates a fragmentary portion of a side of a car which is provided with a door opening 1. Any conventional form of door may be provided for closing

this door opening, and the said door opening is divided into two sections by an upright column 2. A series of horizontally disposed rods 3 which have a spaced and substantially parallel relation to each other are pivotally mounted within bearings 4 provided by crimped portions in upright strips 5 which are secured to the column or post 2. The portions of the rods 3 between the spaced upright bearing strips 5 have crank members 6 rigidly applied thereto, said crank members having their outer ends pivotally connected, as indicated at 7, to an upright bar 8 which is adapted to be moved up and down by means of a hand lever 9 to rotate simultaneously all of the rods 3. The hand lever 9 is shown as extending through an opening 10 in the upright post 2 and pivotally mounted thereon at 11, the forward end of the hand lever having a pin and slot connection 12 with the extremity of the upright bar 8 while the inner end of the hand lever is adapted to be engaged by a suitable latch member 13 to lock the device in operative position.

One end of each of the horizontal bars 3 extends across the portion 1^a of the door opening, and said ends of the rods are curved or deflected outwardly at 3^a so that when swung upwardly they coöperate with each other to form a mail bag receiving cage which is open at the forward side thereof. The other end of each of the rods 3 extends across the portion 1^b of the door opening, and the said ends are curved outwardly at 3^b so that when swung upwardly into operative position they coöperate with each other to provide a mail bag discharging cage. The extremities of the ends 3^b of the rods 3 are journaled within bearings 14 provided by crimped portions in a bearing strip 15 which is secured to the jamb of the door frame 1, the bearings 14 being in horizontal alinement with the respective bearings 4 of the bearing strips 5 applied to the central post 2 so that the horizontal rods 3 are free to rotate in the bearings without any binding action.

When the rods 3 are rotated to swing the outwardly bent ends thereof upwardly into a horizontal plane, as indicated by Fig. 1, the hooked or outwardly deflected ends 3^a of the rods provide a mail bag receiving cage which is open at one side and extends across the forward portion 1^a of the door opening, while the curved ends 3^b of the

rods provide a mail sack discharging cage extending across the portion 1^b of the door opening. A bottom plate 16 is provided for the mail bag receiving cage, said plate being hinged at 17 to the side of the car and being connected at its outer edge by suitable fastening means such as the binding wire 18 to the outwardly bent end 3^a of the lowermost rod 3. A bottom plate 19 is also provided for the mail sack discharging cage, said bottom plate having the inner edge thereof hinged at 20 to the side of the car and being provided at its swinging edge with a pivotally mounted latch member 21 which is adapted to engage a hooked keeper 22 upon the outwardly curved portion 3^b of the lowermost horizontal rod 3. The end of the swinging trip lever 21 projects outwardly beyond the edge of the trap door 19 so that it can be engaged by a suitable trip member at the side of the track, such as the post of an ordinary mail crane 23.

A spring 21^a is connected to the trip lever 21 and normally tends to swing the same into operative position, a suitable stop 21^b being provided to limit the swinging movement of the said lever under the action of the spring. It will also be observed that the end of the hooked keeper 22 is formed with a beveled nose 22^a. With this construction it will be obvious that after the trip lever 21 has been disengaged from the keeper 22 and the trap door or bottom plate 19 permitted to drop so as to discharge a mail sack in the cage provided by the portions 3^b of the horizontal rods, the trip lever 21 can again be brought into engagement with the hooked keeper 22 by swinging the bars 3 downwardly and collapsing the device. The beveled nose 22^a of the hooked keeper 22 will then engage the end of the trip lever 21 and swing the same laterally against the action of the spring 21^a a sufficient amount to admit of the trip lever entering the hooked keeper as soon as it clears the beveled nose 22^a. The trap door or bottom plate 19 can thus be again brought upwardly into operative position after being tripped, by manipulating the hand lever 9 to first collapse the device and then swing the rods outwardly in operative position.

In the operation of the device, the mail sack B to be applied to the car would be suspended by the usual ring 24 from one of the arms of the T shaped head of the crane 23. A mail sack disengaging hook 25 is applied to the frame of the door opening 1, and the end of this hook is designed to engage the ring 24 of the mail sack and slide the same from the arm of the crane 23 without itself entering the ring. As the car passes the crane 23 the ring 24 of the mail sack is thus disengaged from the crane by the action of the hook member 25, with the result that the mail sack drops rearwardly

into the mail receiving cage, from which it can be readily grasped and pulled into the car. The position of the mail sack B while being caught and dropping into the mail sack receiving cage is indicated by dotted lines on Fig. 1. As the car passes the crane 23 the latter will also engage the projecting end of the trip lever 21 so as to swing the same rearwardly away from the hooked keeper 22. The trap door or bottom plate 19 then swings downwardly by the action of gravity so as to discharge a mail sack C previously placed within the mail discharge cage. When the device is not in use the portions 3^a and 3^b of the rods 3 can be swung downwardly and collapsed against the side of the car, although by manipulating the hand lever 9 the device can be swiftly swung upwardly into operative position. The latch 13 will then hold the device securely in operative position until it may be desired to collapse the same again.

Having thus described the invention, what I claim as new and desire to secure by Letters Patent, is:

1. A device of the character described including a collapsible cage constructed to be mounted upon the side of a car and formed of a series of spaced and transversely disposed bars, bearings within which the bars are journaled, said bars having corresponding portions thereof bent laterally for coöperation with each other to form a cage when swung outwardly, and means for simultaneously rotating the bars to collapse the laterally bent portions thereof against the car or swing them outwardly into operative position.

2. A device of the character described including a collapsible cage adapted to be mounted upon the side of a car and formed of a series of spaced and transversely disposed bars, bearings within which the bars are journaled, said bars having corresponding portions thereof deflected laterally for coöperation with each other to provide a cage when swung outwardly into operative position, crank arms rigid with the bars, an upright bar engaging the several crank arms, and means for moving the upright bar to rotate simultaneously all of the transverse bars and swing the outwardly deflected portions thereof against the side of the car or outwardly into operative position.

3. A device of the character described including a collapsible cage constructed to be mounted upon the side of a car and formed of a series of spaced and transversely disposed bars, bearings within which the bars are journaled, said bars having corresponding portions thereof deflected laterally for coöperation with each other to form a cage when swung outwardly into operative position, a swinging bottom plate connected to the lowermost bar so as to move therewith,

crank arms rigid with the bars, an upright bar engaging the several crank arms, and means for moving the upright bar to rotate simultaneously all of the transverse bars and 5 either collapse the laterally deflected portions thereof against the side of the car or swing them outwardly into operative position.

4. A device of the character described including a collapsible cage constructed to be mounted upon the side of a car and formed of a series of spaced and transversely disposed bars, bearings within which the bars are journaled, said bars having corresponding 10 portions thereof deflected laterally for coöperation with each other to provide a cage when swung outwardly, means for simultaneously rotating all of the bars to collapse the laterally deflected portions thereof 15 against the side of the car or swing them outwardly into operative position, a swinging trap door for the bottom of the cage, a trip lever upon the trap door, and a latch member upon the lowermost transverse bar 20 of the cage for coöperation with the trip lever to hold the trap door normally in a raised position.

5. A device of the character described including two upright series of corresponding 25 bearings, spaced and transversely disposed bars journaled within the bearings, the portions of the bars between the bearings being deflected outwardly for coöperation with each other to form a cage when swung outwardly into operative position, and the ends 30 of the bars being extended beyond one set of bearings and correspondingly deflected outwardly for coöperation with each other to provide a second cage when swung outwardly, means for simultaneously rotating 35 the bars to collapse the laterally deflected portions thereof or swing them outwardly into operative position.

6. A device of the character described including two vertical series of corresponding 40 bearings, a series of spaced and transversely disposed bars journaled within the corre-

sponding bearings and having the portions thereof between the two sets of bearings correspondingly deflected laterally for coöperation 50 with each other to form a cage when swung outwardly, said bars being extended beyond one set of the bearings and deflected laterally for coöperation with each other to form a second cage when swung outwardly, 55 means for simultaneously rotating the transverse bars to collapse the outwardly deflected portions thereof or swing them outwardly into operative position, a trap door for the bottom of the first cage, a trip lever 60 for the trap door, and a swinging bottom plate for the second cage connected to the lowermost transverse bar so as to swing therewith.

7. A device of the character described including two vertical series of corresponding bearings, a series of spaced and transversely disposed bars journaled within the bearings and having the portions thereof between the two sets of bearings correspondingly deflected laterally for coöperation with each other to provide a cage when swung outwardly, 65 the ends of the transverse bars being extended beyond one set of bearings and correspondingly deflected laterally for coöperation with each other to form a second cage when swung outwardly, swinging bottoms for the two cages arranged to swing as the lowermost transverse bar is rotated, 70 crank arms rigid with the transverse bars, 75 an upright bar operatively connected to the several crank arms, and means for moving the upright bar to rotate simultaneously all of the transverse bars and swing the outwardly deflected portions thereof downwardly into inoperative position or outwardly into operative position.

In testimony whereof I affix my signature in presence of two witnesses.
